PESSARY

Harry E. Opperman, Sr., and Harry E. Opperman,
Jr., Los Angeles, Calif.

Application October 1, 1945, Serial No. 619,504

4 Claims. (Cl. 128—127)

1

Our invention relates to pessaries, or instruments designed to be introduced into, and worn in, the vagina to support the uterus, or womb, or to remedy a misplacement thereof.

In the devices as used to-day, so far as we know, when these instruments are put into place and worn for a time, and it is desired to remove them, it is difficult to accomplish for the reason that they cling to the uterus because of vacuum tendency and the parts are pulled therewith and cause considerable pain.

The object of our invention is to provide a pessary with a valve which can be released or opened to relieve the vacuum tendency and make it easy and comfortable to remove said instrument.

In order to fully explain our invention, we have illustrated it on the accompanying sheet of drawings, in which:

Figure 1 is an end view of a pessary embodying our invention;

Figure 2 is an end view from the opposite end; and

Figure 3 is a longitudinal sectional view through the body of a pessary, on the line 3—3 of Fig. 1, the handle being shown in side elevation.

Referring in detail to the drawings, the body is designated 4, and has a concaved end, designated 5, with an extension 4', internally threaded to receive a rod, threaded on its inner end, as at 6, said rod being provided with a handle 7 by means of which it can be manipulated.

In the center of the concaved end of the body is a recess 8, with a reduced bore 9, corresponding to the threaded interior of the extension 4', as clearly shown. Said body is also provided with a plurality of vent ports, as 10, one of which is shown in Fig. 3.

Seated in said recess, to fit snugly therein is a valve member 11, having a stem portion 12, extended into the bore of the extension 4' as shown, and in position to be engaged by the inner end of the rod 6, as said rod is screwed into said extension sufficiently to engage and move said valve stem and valve slightly out of said recess 8, as will be clear from the showing in Fig. 3.

When said valve is in its position, as shown in Fig. 3, the concaved surface is smooth, for said valve member is flush with the surface thereof. When in the closed position, as shown, said valve member also covers the inner ends of the vents 10, as shown.

It will be understood, of course, that the handle and rod 6 are removed from the body or instrument when it is to be used, and is only used when it is desired to remove the pessary from the uterus.

By inserting the rod 6 into the vagina and into the extension 4', it can be screwed inwardly sufficiently to unseat the valve member 11, which permits air to enter through the ports 10, and

then the instrument is easily removed, for there can be no vacuum tendency between the concaved surface and the uterus, and it is easily removed.

Any suitable means can be provided to prevent the valve 11 from coming out and being detached from the body. We have shown the valve stem 12 provided with a short groove 13, with a set screw 14 screwed thereinto with its end in said groove, whereby said valve can be moved sufficiently to open it, as will be understood.

We do not limit our invention to the details of construction and arrangement here shown, except as we may be limited by the hereto appended claims.

15 We claim:

1. A pessary provided with a releasable valve and means forming a part thereof and manually operable for releasing said valve to relieve vacuum tendency when it is desired to remove said pessary from the uterus.

2. A pessary consisting of a body and extension, said body having a concaved surface, a valve seat in said concaved surface, a valve seated in said seat, a threaded rod insertable into said extension and operable by turning for opening said valve to relieve vacuum tendency in removing said pessary.

3. A pessary consisting of a body and stem-like portion, said body having a concaved end

30 with a valve seat centrally thereof, a valve with stem seated in said valve seat with its stem extended into the stem-like portion of said body, said body having vent openings leading to said valve seat and closed by said valve, and an operating rod insertable through said stem-like portion of said body and operable for unseating said valve to relieve vacuum tendency when removing said instrument.

4. A pessary consisting of a body having a stem-like portion, said body having a concaved end with valve seat centrally thereof, a valve with stem seated in said valve seat with its stem extended into the stem-like portion of said body, said body having vents leading to said valve seat

45 and closed by said valve in said valve seat, means for preventing said valve from detachment from said body, and an operating rod insertable through said stem-like portion of said body and operable for unseating said valve to relieve vacuum tendency when removing said instrument.
